UNITED STATES PATENT OFFICE.

MARY ALICE JORDAN, OF WASHINGTON, DISTRICT OF COLUMBIA.

EYEGLASS-HOLDER.

SPECIFICATION forming part of Letters Patent No. 746,844, dated December 15, 1903.

Application filed October 7, 1902. Serial No. 126,350. (No model.)

To all whom it may concern:

Be it known that I, MARY ALICE JORDAN, a citizen of the United States of America, and a resident of the city of Washington, in the District of Columbia, have invented certain new and useful Improvements in Eyeglass-Holders, of which the following is a specification.

This invention relates to an improvement in that class of eyeglass-holders which are adapted to be secured to a lady's waist; and the object of my invention is to provide a simple form of holder which shall be capable of being secured in the hair as well as onto a dress.

Prior to my invention it has been common to employ an eyeglass-holder capable of being secured to the dress only, and when such a holder is used it is customary to employ a second holder of the hair-pin variety to supplement the other holder.

It is my purpose to provide one holder to perform the services of both of the holders now in use.

25. My invention therefore consists of an eyeglass-holder provided with means, as a hook, by which the glasses may be held, and with means capable of securing the device both to the dress and in the hair.

30. My invention further consists in the novel construction, arrangement, and combinations of parts, as will be hereinafter more particularly described and then definitely claimed.

35. In the accompanying drawings, which represent the preferable, though not necessary, embodiment of my invention, Figure 1 is a front elevation. Fig. 2 is a rear view. Fig. 3 is a top plan showing the teeth or securing-pins closed. Fig. 4 is a similar view of the teeth and securing-pins held open. Fig. 5 is a vertical section through the line *a b* of Fig. 3.

40. Referring now to the details of the drawings by numerals, 1 indicates a spindle around which the other parts of my device are arranged, and this spindle has an enlarged upper end 2, formed to simulate the head of a butterfly. To this head is secured a ring 3, to which is connected the usual chain 4 for connection with the eyeglasses.

45. On the spindle 1 I pivot two plates 5 and 6,

each of which is formed with ears 5^a and 6^a, which are perforated to fit over the said spindle 1, so as to turn thereon in a manner somewhat similar to that in which the leaves of a hinge turn.

Surrounding the spindle 1 and located between the ears 5^a and 6^a is a coiled spring 8, one end of which passes through the plate 5, as shown at 9, and the other passes through the plate 6, as shown at 10. This spring is for the purpose of holding the parts in the positions shown at Fig. 3, and to prevent the spring from moving the plates 5 and 6 too far I form the rear edges of said plates so as to 55 abut against each other, as shown at 11.

To the rear side of each of the plates 5 and 6 I secure a plurality of teeth or securing means 12 and 13, which are specially constructed to lap over each other, as shown in 60 Fig. 3, for the purpose hereinafter described.

In order to form the support for holding the eyeglasses when not in use, I employ a hook 15, which may be similar to the hooks now in use, although when used on a butterfly form of holder the face of the hook will be formed to simulate the body of the butterfly. The rear of this hook is bent upwardly and formed into a curved plate 16, which effectively hides the spring 8 from view. The upper end of this plate is formed with an ear 17, perforated to fit over the spindle 8, so as to hold the same in position. In some cases this ear 17 will be sufficient; but I prefer to employ a similar ear 18, projecting from the 75 bottom of the curved plate 16 and which contacts with the lower end of the spindle 8, and thus very effectually holds the plate 16 and its hook 15 in place.

The plates 5 and 6, which have been mentioned as being supported on spindle 1, may be ornamented in any desirable manner; but in my drawings I have shown two plates 19 and 20 riveted to the plates 5 and 6, and said plates 19 and 20 are formed and ornamented 80 to have the appearance of the wings of the butterfly. It will be obvious from an inspection of Figs. 3 and 4 that by grasping the two plates 19 and 20 with the thumb and index finger the plates may be moved on their pivot 85 1 so as to open the teeth or securing-pins 12 and 13, and the coiled spring 8 is of sufficient

strength to return said parts to their normal positions as soon as the inward pressure on the plates 19 and 20 is relieved.

It follows from the construction described that when the user desires to secure the holder to a dress or in the hair all that is necessary to do is to grasp the plates 19 and 20 with sufficient pressure to open the teeth or securing-pins, and then by placing the said teeth 5 in a proper position against a dress or against a strand of hair the teeth may be secured to the dress or hair by simply releasing the plates 19 and 20.

I regard the formation of the teeth or securing means as very important, for the reason that they must be so situated with respect to each other as to grasp a thick strand of hair as well as to readily puncture a piece of smooth dress goods. I therefore form the 15 teeth or securing means with very sharp points, which lap over each other and when closed touch each other on their horizontal surfaces, so as to prevent the hair from escaping from the teeth and thus permitting the 20 holder to drop off.

I am familiar with the fact that it has heretofore been proposed to form an eyeglass-holder with two springy hooks or points to engage the dress, as may be seen in Patent No. 30 526,519. I am also aware of holders like that shown in Patent No. 392,367, which shows two spring-actuated hooks adapted to puncture a dress. These devices, however, as well as quite a number of others which have been 35 proposed, while quite effective for securing the holder to a piece of dress goods, are

wholly ineffective if used for securing a holder to the hair. I therefore do not claim these as my invention, but regard my holder as essentially different therefrom. At the same 40 time I desire it understood that I do not limit my claims to the precise form shown in the drawings and herein described, as the form shown is merely my preferable embodiment.

What I claim as new is—

1. As a new article of manufacture, an eye-glass-holder comprising a pivotal pin having its upper end representing a head; plates pivoted on said pivotal pin and formed to represent wings and having teeth on their 50 rear sides, and a hook located between said plates and simulating a body and formed to have the glasses hooked thereon; substantially as described.

2. As a new article of manufacture, an eye-glass-holder comprising a pivotal pin having its upper end representing a head; plates pivoted on said pivotal pin and formed to represent wings and having teeth on their rear sides, said teeth overlapping and being 60 in close contact with each other whereby they are adapted both to secure the holder to a dress and to a strand of hair, and a hook located between said plates and simulating a body and formed to have the glasses hooked 65 thereon; substantially as described.

Signed by me this 4th day of October, 1902.

MARY ALICE JORDAN.
